FIG. 7

INVENTOR

John L. Martin
BY
O. M. Clarke
ATTORNEY

UNITED STATES PATENT OFFICE.

JOHN L. MARTIN, OF PITTSBURGH, PENNSYLVANIA.

FOOT EXERCISER.

Application filed August 29, 1922. Serial No. 585,009.

To all whom it may concern:

Be it known that I, JOHN L. MARTIN, a citizen of the United States, residing at Pittsburgh, in the county of Allegheny and 5 State of Pennsylvania, have invented certain new and useful Improvements in Foot Exercisers, of which the following is a specification.

My invention consists of an improved device for exercising the feet, and especially 10 for the purpose of correcting malformations, defects, or weaknesses, and development of a normal condition. The particular object in view is the correction or cure 15 of "fallen" arches, due to various causes.

Ordinarily, these defects are treated by the insertion in footwear of upwardly projecting bearing portions for the sole of the foot, tending to elevate it more or less. In 20 my invention, I provide means for exerting upward pressure both longitudinally of the foot and transversely, and at the same time varying the direction of pressure of the weight of the body in variously changing 25 directions. This is done by means of a rocking platform or pedal, constructed and adapted to operate in the manner hereinafter described.

In the drawings, showing one preferred 30 form of the invention:

Fig. 1 is a view of the device in side elevation;

Fig. 2 is a plan view of Fig. 1;

Fig. 3 is a view in rear elevation;

35 Figs. 4 and 5 are cross sections on the lines IV-IV and V-V of Fig. 2;

Fig. 6 is a view showing the manner of using the device; and

40 Fig. 7 is a similar view showing the device provided with a controlling stem.

In general, I provide a rocking support having an upper double sided foot supporting shelf, variously curved to fit against the soles of the feet, when placed theron side by 45 side, in an over-corrected position. A central upwardly extending rounded ridge 2 widening towards the rear, merges downwardly at each side into the foot supporting surfaces 3-4-5 at each side.

50 Of these, the portion 3, which supports the front under part of the foot immediately back of the toes, is curved both longitudinally and transversely, and slightly more convex in both directions than the middle portion 4. Such middle portion slopes backwardly, gradually flattening, and merging

into the portion 5 which is recessed or concaved in both directions, providing heel sockets at the rear.

These various surfaces are within the surrounding edge 6, curved as shown in Fig. 2 to form an approximation of the outline of the outline of the foot area, when together in the over-corrected position. The supporting shelf, bounded by the vertically and laterally undulating edge 6, extends outwardly from the upper portion of a base 7, forming the middle body portion of the device. A rocker bottom 8 extends downwardly from the base and is provided with a 70 rounded, somewhat elongated, contour 9 adapted to make contact with and roll over a flat horizontal surface 10 to a limited extent as an ordinary floor, until arrested by one of the edges of the base, or of the shelf 75 itself, thus limiting the tilt.

Staples 11 extend outwardly from each side of the base 7, to which are attached the side straps 12 having terminal loops 13, with means for lengthening or shortening, as 80 buckles, or the like, to accommodate the height of the operator.

In Fig. 7, I show a modified construction in which the implement is provided with a centrally arranged controlling stem or post 85 14 inserted in a suitable socket 15 midway of its width, to assist the operator in place of the straps 12 or other external support. Post 14 is socketed slightly forward of the middle, through ridge 2, with sufficient forward inclination to ensure clearance for the body. As indicated by the line $x-x$, representing the extreme rearward tipping position, the post is substantially at right angles to such line, so that when 95 tipped backwardly, the post will be erect.

In operation, the user stands on the implement, with both feet snugly set upon the surfaces 3-4-5 at each side, as in Fig. 6, maintaining balance by the side straps 12, or by holding any suitable object, as a bedstead, mantel, or chair. With the heels firmly planted in sockets 5 and the toes brought close together and overhanging the front edges, the arches of the feet rest upon the 100 upwardly rounded intermediate portions 4, fitting snugly against the intermediate tapering ridge 2.

Rocking motion in all directions, and especially forwardly, backwardly, and sidewise, 110 tends to continually exercise the muscles, ligaments, and tendons, stimulating circu-

lation, and setting the bony structure towards its proper position and relation, and restoring the bony articulations of the foot to their normal positions. Continued repetitions of such exercises, at frequent intervals, will eventually effect a permanent change in the form of defective feet, and give permanent relief by renewing the sustaining power of the arches, in the manner described.

The device may be made of any suitable metal, as aluminum, brass, iron, etc., in which case it is preferably cast hollow of two connected pieces, as shown, for lightness. However, it may also be of wood, in one solid carved piece, or of rubber, pressed fibre, or other suitable material, and in suitable sizes for different sizes and weights of the various users. It may also be changed or varied in detail construction by the skilled mechanic within the scope of the following claims.

What I claim is:

1. A foot exerciser having a rounded supporting bottom and an upper portion having foot receiving surfaces and a dividing ridge.
2. A foot exerciser having a rounded supporting bottom and an upper portion having foot receiving surfaces crowned at the

middle and sloping downwardly towards each end.

3. A foot exerciser having a rounded supporting bottom and an upper portion having foot receiving surfaces at each side of a longitudinal ridge rounded upwardly at the middle with a heel socket at one end.

4. A foot exerciser having a rounded supporting bottom and an upper portion having foot receiving surfaces at each side of a longitudinal ridge rounded upwardly at the middle with a heel socket at one end and a downwardly sloping portion at the other.

5. A rocking bottom foot support provided with upwardly arched feet receiving faces at each side of a topmost ridge.

6. A rocking bottom foot support provided with upwardly arched feet receiving faces at each side of a forwardly narrowing ridge.

7. A rocking bottom foot support provided with upwardly arched feet receiving faces at each side of a topmost ridge, and means for grasping and steadyng the device in use.

8. A rocking bottom foot support provided with upwardly arched feet receiving faces at each side of a topmost ridge, and a pair of side holding straps.

In testimony whereof I hereunto affix my signature.

JOHN L. MARTIN.
